UNITED STATES PATENT OFFICE.

HARRY J. WINSTEN, OF READING, PENNSYLVANIA, ASSIGNOR TO SCHUYLKILL SILK MILLS, OF READING, PENNSYLVANIA, A CORPORATION OF PENNSYLVANIA.

DESIGN FOR AN UNDERGARMENT.

53,095.

Specification for Design.

Patented Mar. 11, 1919.

Application filed November 14, 1917. Serial No. 202,062. Term of patent 14 years.

To all whom it may concern:

Be it known that I, HARRY J. WINSTEN, a citizen of the United States, residing at Reading, in the county of Berks and State of Pennsylvania, have invented a new, original, and ornamental Design for Undergarments, as shown in the accompanying drawing and described in the following specification.

This garment consists of a bifurcated petticoat, having a full body portion 2, gathered at the waist 3, the tubes 4 for the limbs being of extreme fullness constricted at the knees and then gathered in ruffles at 5. Wide and deep ruffled cuffs 6—6 are attached to the tubes and are upwardly converged toward the line of stitches 7 and above this again ruffled to their edges which flare slightly.

I claim:

The ornamental design for an undergarment as shown and described.

HARRY J. WINSTEN.
